UNITED STATES PATENT OFFICE.

MAEQUIS H. LOCKWOOD, OF NEW YORK, N. Y., ASSIGNOR TO PUBLIC SERVICE CUP COMPANY, OF BROOKLYN, NEW YORK, A CORPORATION OF NEW YORK.

CUP-DISPENSER.

1,289,487.

Specification of Letters Patent. Patented Dec. 31, 1918

Application filed March 25, 1916. Serial No. 86,537.

To all whom it may concern:

Be it known that I, MARQUIS H. Lockwood, a citizen of the United States, and a resident of the borough of Manhattan, city, county, and State of New York, have invented certain new and useful Improvements in Cup-Dispensers, of which the following is a specification.

My invention relates more particularly to cup-dispensers adapted to hold a stack of nested flanged cups from which the lowermost cup may be separated or discharged by manual means. It has been usual with cup-dispensers of this kind to support the stack of cups in such a manner that the lowermost cup protrudes through the bottom opening and may be grasped by the hand and withdrawn, the stack of cups being supported by the flanged edges of the lowermost cup in such a manner that to withdraw the lowermost cup the flange must be distorted. Supporting the cups in this manner and being compelled to forcibly draw the flange of the cup through a narrow opening or past a member adapted to flex or distort the flange, is objectionable in that injury to the cup may result therefrom.

The object of my invention is to provide a cup-dispenser, the outlet opening of which is of sufficient diameter to permit the free passage of the cup flanges therethrough without requiring that they should be distorted in any manner. In carrying out this invention, I have devised a form of fixed escape- 35 ment in which the cups are removed through a zig-zag passage or outlet opening formed in the annular support for the cup-receiver. The principle of the device is such that inwardly projecting ribs or flanges are preferably provided at different levels and eccentrically arranged with respect to each other and to the axis of the receiver, the stack of cups being normally supported by one of the ribs or flanges. In order to remove a cup, in the herein-described adaptation of my invention, the lowermost cup is grasped by the hand and the entire stack of cups is bodily moved off of the lower rib or flange which normally supports the stack of cups, or until the edge of the lowermost cup flange is freed from the normally supporting rib or flange of the device and the opposite rib is brought into play to support the stack of cups, temporarily, by engaging the flange

of the next to the lowermost cup, thus permitting the separation and removal of the lowermost cup. As soon as the lowermost cup has been removed in this manner, the stack of cups is adapted to immediately slide off of the temporary holding rib flange of the support and again rest upon and be supported by the other rib in the normal position.

One form of my invention is illustrated in the accompanying drawings, in which—

Fig. 1 represents a front elevation of the cup-dispenser.

Fig. 2 represents a vertical cross-section of the device taken from front to back thereof.

Fig. 3 represents a transverse cross-section on the line 3—3 of Fig. 2 without showing the cups.

Fig. 4 is another transverse cross-section on the line 4—4 of Fig. 2 just above the lowermost eccentric rib; and

Fig. 5 is a section similar to that shown in Fig. 2 representing the position of the cups when the cup stack is moved transversely to remove the lowermost cup.

Referring to the drawings, A represents the receiver for a stack of nested flanged cups, the receiver preferably being a glass tube with closed upper end and of a diameter slightly larger than the diameter of the cup flanges. The lower end of the tube is open and is adapted to be supported in an annular supporting member B which is preferably formed with a counter-bore C to fit the receiver and support the same on an internal ledge substantially as indicated in Figs. 2 and 5 of the drawings. Immediately below this ledge or internal shoulder I provide an eccentric rib or flange D which is preferably beveled on its upper face and of sufficient width to enter between the successive cup flanges of the stack of cups E. The rib or flange D extends crescent-like around one side, preferably the front, of the support B and provides a circular opening of a diameter but slightly larger than the cup flanges so that the latter are adapted to pass freely therethrough. Immediately below the eccentric rib or flange D, I preferably provide a second eccentric rib or flange F, not only eccentric with respect to the cup-receiver but eccentric of the other rib or flange D. It is, however, located on the diametrically opposite side of the axis of the

receiver, that at the back of the support as indicated in Figs. 3 and 4 of the drawings. The flange F is preferably spaced so that its upper surface is an appreciable distance below the lower surface of the flange D, the space being such as to exceed the thickness of the cup flanges E' by an appreciable amount, thereby permitting the latter to clear the lower edge of the flange or rib D when the cups are normally resting upon the eccentric rib F, as indicated in Fig. 2 of the drawings.

The ribs or flanges D and F may be formed in any desired manner but preferably they are formed integral with the annular support or member B and the circular opening therein are made continuous with the walls of the annular support, substantially as indicated in Figs. 3 and 4 of the drawings, where it will be seen that the eccentric ribs or flanges gradually thin out and disappear in the wall of the member B. In this manner the flanges become a part of the outlet openings for the cups and provide a passage (zig-zag or sinuous in form) which is of sufficient diameter to permit the free passage of the cup flanges therethrough without distorting them in any way. The member B and the entire device may be supported in any preferred manner, as for instance, by a bracket G, provided with screw holes at H for attaching the same to the wall or other permanent support.

In operation the cups are preferably arranged in nested form in a stack of suitable or convenient height and placed in the receiver A, which is adapted to protect the same from dust or other contamination and also act as a guide for preventing the stack of cups from falling over. Normally, the lowermost cup rests, in the present form of the device, upon the lower flange or rib F, as indicated in Fig. 2 of the drawings, the lowermost cup in this view being shown in section. It will be seen that the flange of the lowermost cup rests upon the rib or flange F, which, as shown, is provided with a flat upper surface adapted to act as a permanent or normal support for the stack of cups. If now the lowermost cup is grasped by the hand and the entire stack is drawn forward (toward the left in Fig. 2), the flange of the next to the lowermost cup will strike the inclined face of the rib D and ride up the same and assume a position, substantially as indicated in Fig. 5 of the drawings, in which position the rib D acts as a temporary support for the stack of cups and the lowermost cup is free to be withdrawn because its flange E' is below the rib D and clear of the rib F and can freely pass through the eccentric circular opening defined by the rib F and the wall of the support B. As soon as the lowermost cup, as indicated in Fig. 5, is removed from the

stack, the entire stack, resting temporarily upon the beveled face of the rib D, will slide down the same and return to the normal position with the flange of the lowermost cup engaging the rib F, as indicated in Fig. 70. It will thus be seen that the ribs or flanges D and F act something like an escapement which permits the removal of a single cup at a time by bodily shifting the stack of cups from the normal supporting 75 rib or flange to the temporarily supporting rib or flange and withdrawing the lowermost cup.

It will be understood that the shape of the escapement ribs may be varied and the number and location thereof changed to meet requirements for different styles of cups and the way they are to be delivered, and various modifications in the specific details of construction of the device may be made without departing from the spirit and scope of the invention.

I claim—

1. A dispenser for nested cups comprising a receiver for holding a stack of cups and a support for the receiver provided with a discharge opening of sufficient diameter for the free passage of a cup therethrough, said opening being defined by eccentrically arranged circular flanges in different planes 90 having their centers on opposite sides of the axis of the receiver whereby a movement of the cups transversely of the receiver is required to separate and remove a cup.

2. A dispenser for nested cups comprising a receiver for holding a stack of cups and a support for the receiver provided with a discharge opening having an inwardly extending flange adapted normally to support the stack of cups by supporting the lowermost cup on one side thereof and an oppositely disposed flange adapted to temporarily support the stack of cups by engagement with the next to the bottom cup when the stack of cups is moved bodily off of the first named flange to separate the bottom cup from the stack.

3. A dispenser for nested cups comprising a receiver for holding a stack of cups and a support for the receiver provided with a discharge opening of sufficient diameter for the free passage of a cup therethrough, said opening being formed zig-zag by two eccentrically arranged circular flanges extending inward from said support in different transverse planes and having their centers on opposite sides of the axis of said receiver, one of said flanges being adapted to support the cups normally, the other being adapted to support the stack temporarily when the stack is bodily moved off of the first named flange to separate the lowermost cup.

4. A dispenser for nested cups comprising a receiver for holding a stack of cups, a support for the receiver provided with a

discharge opening of sufficient diameter for the free passage of a cup therethrough, and means for permitting the removal of said cups singly through said opening comprising 5 oppositely disposed flanges, symmetrically arranged with respect to the axis of said receiver, one for normally supporting the stack of cups and the other for temporarily supporting the stack, the latter coming into play only when the stack is moved bodily off the normally supporting flange to separate the lowermost cup from the stack.

5. A dispenser for nested cups comprising a receiver for holding a stack of cups, 15 an annular support having a counterbored portion adapted to fit the outside of the receiver, a segmental rib extending inward from the wall of said support and defining a circular opening eccentric of said receiver and a second segmental rib located below and spaced from the first flange also defining a circular opening eccentric of said receiver, said openings being displaced so as to be eccentric to each other and of such 25 diameter as to permit the free passage of a cup therethrough.

6. A dispenser for nested cups from which the cups are to be withdrawn manually comprising a receiver for holding a stack of cups, an annular support for the receiver provided with eccentrically arranged ribs for supporting the stack of cups one of said ribs being in a plane below the other and adapted to support the cups normally, the other rib being beveled and adapted to support the stack temporarily when the stack is moved bodily off of the lower rib for the removal of the lowermost cup.

7. A dispenser for nested cups comprising 40 a receiver for holding a stack of cups, an annular support for the receiver provided with a pair of eccentrically arranged inwardly extending ribs, said ribs being spaced apart longitudinally of the stack of cups 45 and adapted to alternately act as a support for the cups when the stack is bodily moved from one to the other for the removal of the lowermost cup.

8. A dispenser for flanged nested cups 50 comprising a receiver for holding a stack of cups and an annular support for the receiver provided with crescent shaped inwardly extending ribs located on opposite sides of said annular support for supporting 55 the stack of cups, the rib on one side acting normally as a support for the stack of cups, the other rib being adapted to support the stack temporarily when the same is bodily

shifted off of said normal support for the removal of the lowermost cup. 60

9. A dispenser for flanged nested cups comprising a receiver for holding a stack of cups and an annular support for the receiver provided with means comprising inwardly projecting eccentric annular flanges 65 coöperating with the flanges of the cups for supporting the same whereby the cups may be withdrawn singly by shifting the stack of cups bodily transversely of said supporting means. 70

10. A dispenser for flanged nested cups comprising a receiver for holding a stack of cups and an annular support for the receiver provided with inwardly projecting means on one side of the central axis of the 75 receiver adapted to coöperate with the flange of the lowermost cup of the stack for normally supporting the stack, and means on the opposite side of the central axis adapted to coöperate with the flange of the next succeeding cup of the stack and temporarily support the stack when the same is bodily shifted off of the normally supporting means for the removal of the lowermost cup. 80

11. A cup dispenser comprising an open 85 mouthed container for a vertically disposed stack of nested flanged cups, and rigid eccentric flanges mounted therein at the mouth of the container for discharging cups one at a time by lateral movement of the stack. 90

12. A cup dispenser comprising a container for a vertically disposed stack of nested flanged cups having an opening at its lower end through which cups may be discharged, and rigid means comprising eccentric annular flanges mounted within said opening for discharging cups one at a time by lateral movement of the stack, the inside diameter of the opening defined by said annular flanges being greater at any given 100 horizontal plane than that of a cup flange. 95

13. A cup dispenser including in combination a stationary container for a stack of nested flanged cups having an opening at its lower end, a fixed primary support within said opening for at one time engaging the lowermost cup and a fixed secondary support within said opening for at another time engaging the next to the lowermost cup, said secondary support being effective to temporarily support the stack during removal of the lowermost cup and to guide the stack to supporting engagement with said primary support. 105 110

MARQUIS H. LOCKWOOD.
